UNITED STATES PATENT OFFICE.

DENYS WARWICK MORLEY, OF VICTORIA, HONGKONG, ASSIGNOR TO UNITED SHOE MACHINERY CORPORATION, OF PATERSON, NEW JERSEY, A CORPORATION OF NEW JERSEY.

SEWING MACHINE.

Application filed April 3, 1923, Serial No. 629,685, and in Great Britain April 5, 1922.

The invention relates to boot or shoe or like sewing machines which embody a rotary work supporting horn (wherein operates a looper) and a barbed needle and especially 5 to machines such as described in U. S. application No. 442,040, filed February 3, 1921, upon which Patent No. 1,521,288 issued, dated December 30, 1924, Gouldbourn & Ricks.

10 The principal objects of the invention are to adapt a machine as described in said specifications more readily to deal with shoes of widely differing thicknesses of bottom and with shoes requiring widely differing lengths 15 of stitch. Another object of the invention is to render the mechanism of such a machine more robust and less liable to wear.

One feature of the invention is a rotary-horn barbed-needle chainstitch sewing machine wherein the horn calipers the work and by its movement according to changes 20 of work thickness automatically controls the position to which the needle moves in both directions so as to project the needle through 25 the work for the looping by always the same amount into the horn and to draw a loop which varies in length, from the face of the work from which it emerges, as the work thickness varies.

30 Another feature of the invention is a rotary-horn barbed needle chainstitch sewing machine comprising means to vary the length of loop drawn out of the work as an incident of adjustment of the work-feed 35 mechanism to sew stitches of different length.

Still a further feature of the invention is a needle-actuating mechanism for a rotary-horn barbed needle chainstitch sewing machine the horn whereof controls the needle stroke which mechanism comprises a crank 40 or like rotary actuator and a link-connection therefrom to the rest of the mechanism such that the point of connection of the link and the rotary actuator on the one hand and the point of connection of the link and the driven mechanism on the other hand lie at the time the needle comes to the thread receiving end of its stroke at opposite sides of 45 the axis of the rotary actuator, thereby increasing the dwell at this end of the needle stroke and permitting the use of a looper rotating but twice for each needle reciproca- 50 tion instead of three times as formerly.

These and other objects and features of the invention will become more fully evident from the following description of constructions embodying the invention.

In the drawings Fig. 1 is a side elevation partly in section showing so much of the 55 sewing machine of the above application as is necessary to illustrate the application of one form of the present invention thereto; Fig. 2 is a detailed side elevation of the needle actuating and controlling mechanism showing in full lines the position of the parts when the needle bar is fully raised and diagrammatically in dot-and-dash lines the position of the parts when a thicker piece of work is being operated upon; Fig. 3 shows 60 diagrammatically in full lines the needle bar and actuating mechanism in fully lowered position and in dot-and-dash lines the position of these parts when operating on the same thicker piece of work; Fig. 4 is a partial view similar to Fig. 1 showing a second 65 form of needle actuating and controlling mechanism embodying the invention; Fig. 5 is a detailed sectional elevation showing a 70 part of the connections through which the vertical movement of the horn in calipering the work controls the needle stroke; Fig. 6 is a front elevation partly in section of the mechanism shown in Fig. 5; Fig. 7 is a detailed front elevation of the needle actuating and controlling mechanism of Figs. 4 and 6 showing in full and dot-and-dash lines 75 the position of the parts at the upper end of the needle stroke in operating upon two different thicknesses of work and Fig. 8 shows 80 diagrammatically in full and dot-and-dash lines the position of the parts at the lower end of the needle stroke when operating upon the different thicknesses of work.

The machine shown is provided with the 85 rotary and vertically movable horn 2 carrying in its tip the rotary looper 4, a barbed needle 6 carried by a vertically reciprocating needle bar, a cast-off 8, a presser foot 10, and a feed point 12, all of which, with the exception of the looper and needle bar, are operated and controlled as in the machine shown and described in the application above referred to. The looper is rotated from the cam shaft 14 through a train of gearing and 90 shafting similar to that of the machine of the above application but the gearing is proportioned to give the looper two revolutions 100 instead of three times as formerly.

for each revolution of the cam shaft instead of three revolutions as heretofore. The horn is raised and lowered as in the machine of the above application through a treadle 6 lever 16, the forward end of which is connected by links 18 with a yoke in which the horn rotates and the rear end of which is connected by a rod 20 with a lever 22 so that the vertical position of the lever varies 10 with the vertical position of the horn in caliper 15 the work. The lever and horn are locked against vertical movement during a part of each cycle by a locking device indicated at 24 which is operated by a cam on the cam shaft to lock and release a vertical rod 26, the lower end of which is pivoted to the horn controlled lever 22.

Two needle actuating mechanisms are shown which may be controlled from the 20 horn to vary the position to which the needle moves in both directions according to the thickness of the work caliper 15 by the horn.

In the first construction (shown in Figs. 25 1, 2 and 3 of the drawings) the needle bar operating bell crank lever 28 has its depending arm 30 coupled by an upwardly and rearwardly extending link 32 directly and by a universal joint to the lower end of the 30 connecting rod 34 which hangs from the ball-shaped crank pin 36, the arrangement being such that when the needle 6 is at the bottom of its stroke the crank 36 is in its uppermost position (as shown in Fig. 3) so 35 that the slower rising and falling movement occurs at the lower end of the needle stroke and not at the upper end as in the previous construction and time is gained which permits of using a looper rotating but twice for each needle reciprocation instead of the three to one looper necessary with the previous construction and somewhat subject to wear and tear.

The pivotal connection of the link 32 and 45 rod 34 is pivoted to one end of a somewhat shorter link 38 extending forwardly, its other end being connected by a considerably longer and downwardly and rearwardly extending link 40 to the horizontal horn controlled lever 22 in the machine head and by 50 a rearwardly extending link 42 only slightly longer than itself to a pivot point 44 on the frame which is at all times somewhat below the point 46 of interconnection of the three 55 links 38, 40 and 42 and lies between the highest and lowest points of the throw of the lower end of the connecting rod 34 and somewhat below the level of the pivot of the needle operating bell crank lever 28.

60 In the second construction (shown in Figs. 4, 6, 7 and 8) in which the links and levers of the mechanism lie across the machine instead of, as in the first construction, lengthwise of the machine, the needle bar 65 operating bell crank lever 48 has its arm 50

pivoted to one end of a link 52, the other end of which is connected by a link 54 to one arm of a lever 56 pivoted at 58 to the machine frame. The other arm of the lever 56 is connected by a link 60 to a 70 crank arm 62 fixed on the driving shaft 14. Also pivoted by a universal coupling to the connecting point 64 of the links 52 and 54 is a link 66 which at its lower end is connected at 68 by a universal coupling to the horizontal horn controlled lever 22 which extends from front to rear of the machine and which in this construction is so formed that the pivotal point 68 is lowered as the horn is lowered. 75

The whole arrangement in each construction is such that if the point 46 or 64 of interconnection of the three links 38, 40 and 42 or 52, 54 and 66 is moved by the horn in response to increased thickness of the work and shown in dot-and-dash lines in the drawings the lowest position to which the mechanism will move the needle is lowered substantially by the amount that the work is increased in thickness while the highest position to which the mechanism will move the needle is raised by a smaller amount than the work has increased in thickness but enough to draw a loop of a sufficiently greater length above the work. 95 With diminishing thickness of work a similar result in diminishing the needle stroke curves, i. e., the whole stroke is reduced, but more at the bottom than at the top end.

The length of loop drawn out above the work by the needle should not only vary with the thickness of the work but should also vary with the length of feed since a shorter stitch requires less thread and a shorter loop. The length of loop drawn 105 above the work obviously depends upon the height of the lower surface of the presser foot 10 and as it is important at all lengths of feed that the presser foot should be as close to the sewing point as possible the 110 presser foot is made adjustable to and from the sewing point on the lower end of the presser foot vertical bar 70 and advantage is taken of this to insure coincident change of the length of loop drawn above the work (as 115 the position of the foot is changed for different feeds) by providing for the purpose of the adjustment of the foot upon its bar a rectilinear tongue 72 on the bar 70 and a groove 74 on the presser foot which are inclined upwardly towards the sewing point sufficiently to cause the foot to be raised by the amount that the loop length is to be correspondingly shortened as the presser foot 120 is set nearer the sewing point for any particular length of feed.

The invention having been thus described, what is claimed is:

1. A sewing machine having, in combination, a needle, needle actuating mechanism, a 130

work support, the vertical position of which varies with changes in the thickness of the work, and means acting automatically to control the needle actuating mechanism to 5 vary the position to which the needle is moved in both directions according to the changes of work thickness.

2. A sewing machine having, in combination, a needle, a work support movable to 10 caliper the work, and needle actuating mechanism controlled from the work support to project the needle a uniform distance through varying thicknesses of work and to draw a loop which varies in length from 15 the face of the work as the work thickness varies.

3. A sewing machine having, in combination, a needle, a rotary work supporting horn movable to caliper the work, and needle 20 actuating mechanism through which the horn by its movement according to changes of work thickness automatically varies the position to which the needle moves in both directions.

25 4. A sewing machine having, in combination, a needle, a work supporting horn movable to caliper the work, and needle actuating mechanism controlled by the position of the horn to project the needle a uniform distance into the horn and to draw above the upper face of the work a length of loop varying as the work thickness varies.

5. A sewing machine having, in combination, a needle, a work supporting horn movable to caliper the work, and needle actuating mechanism controlled by the position of the horn to vary both the upper and lower 35 limits of the needle stroke.

6. A sewing machine having, in combination, a needle, a work supporting horn movable to caliper the work, and needle actuating mechanism controlled by the position of the horn to vary the movement of the needle at the lower end of its stroke an amount 40 equal to the variation in the work thickness and at the upper end of its stroke a less amount.

7. A sewing machine having, in combination, a needle, mechanism for actuating the 50 needle comprising a series of relatively movable parts to maintain the needle under positive control throughout its stroke, a presser foot, a work support movable toward and from the presser foot, and a connection between the work support and needle actuating mechanism acting to vary both the needle penetrating stroke and the loop drawing stroke upon a change in the position of the work support.

60 8. A sewing machine having, in combination, a needle, mechanism for actuating the needle comprising pivotally connected links

movable about different centers, one of which centers is on one side of the other at one limit of the needle stroke, and on the opposite side of the other at the other limit of the needle stroke, a presser foot, a work support, and a connection acting upon a change in the relative positions of the presser foot and work support to swing the pivotal connection of said links about one of said centers to increase or diminish the movement of the needle at both ends of its stroke. 65

9. A sewing machine having, in combination, a needle, mechanism for actuating the 70 needle comprising pivotally connected links movable about different centers, means for moving one center about the pivotal connection of the links from one side to the other of the other center in moving the needle from one limit of its stroke to the other, and means for caliper the work connected to swing the pivotal connections of the link about the first center to vary the limit of the needle movement at both ends of its stroke. 75

10. A sewing machine having, in combination, a needle, mechanism for actuating the needle comprising an oscillating lever, two pivotally connected links, a pivotal connection between one of said links and the 80 lever, connections between the other link and the needle, and work caliper means connected to swing the pivotal connections of the links about the pivotal connection of the oscillating lever to vary the limit of the 85 needle movement at both ends of its stroke.

11. A sewing machine having, in combination, a barbed needle mounted to move during each stroke to a thread receiving position, a work supporting horn, needle actuating mechanism comprising a crank, a link connection having its point of connection with the crank and its point of connection with the rest of the mechanism on opposite sides of the axis of the crank when the needle is at the thread receiving end of its stroke, and a rotary looper in the horn which makes two revolutions for each reciprocation of the needle. 100

12. A sewing machine having, in combination, a barbed needle mounted to move during each stroke to a thread receiving position, a work supporting horn movable to caliper the work, needle actuating mechanism controlled by the horn and comprising 105 a crank, a link connection having its point of connection with the crank and its point of connection with the rest of the mechanism on opposite sides of the axis of the crank when the needle is at the thread receiving end of its stroke, and a rotary looper in the horn which makes two revolutions for each reciprocation of the needle. 110

DENYS WARWICK MORLEY.
